UNITED STATES PATENT OFFICE

RALPH E. BATEMAN, OF DETROIT, MICHIGAN

PRODUCTION OF VARICOLORED EFFECTS

Application filed April 27, 1927, Serial No. 186,923. Renewed January 11, 1929.

The present invention relates to the production of varicolored effects in coating surfaces and to apparatus therefor.

Among the objects of the invention is to enable an operator to readily produce a color change either abruptly or gradually when applying liquid coloring material to a surface.

Other objects will readily appear to those skilled in the art upon reference to the following description and accompanying drawing in which:—

Fig. 1 is a longitudinal vertical section through a spray gun suitable for the coating operation;

Fig. 2 is a longitudinal section on line 2—2 of Fig. 1; and

Fig. 3 is a section on line 3—3 of Fig. 1.

As indicated in the drawings, the operation is best carried out with a novel spray gun such as shown. In this form of gun, the body portion 10 provided with a pistol grip portion 11 is also provided with a longitudinal air passage 12 connected by hose 13 with a source of air under pressure.

The air passage 12 is controlled by a needle valve 15 carrying a laterally enlarged portion 16 against which operate a pair of cams 17 and 18. These cams are movable vertically either together or separately by means of a pair of triggers 20 and 21 which carry pins 22 contacting with the lower sloping end 23 of cams 17 and 18.

Beyond valve 15 the passage 12 is divided and the two branches lead to opposed jets 25 in the nozzle 30.

Nozzle 30, in addition to the two longitudinal air passages, is provided with a longitudinal passage 31 leading to a point between jets 25 and connects with a horizontal cross passage 32. This cross passage 32 is connected at its ends through tubes 33 to the lower portions of two closed liquid color containers 34 and 35 and is valved on either side of passage 31 as by the cut off valves 36 and 37.

The valves 36 and 37 are connected to and operated by the two triggers 21 and 20 respectively so that, as either trigger is pulled,

it opens simultaneously both the valve 15 and its corresponding gate or cut-off valve.

In order to obtain instantaneous color flow to the nozzle it is preferred to put the color in containers 34 and 35 under pressure and this is done by connecting them through a T 40 connected by a hose 41 to a suitable source of air under pressure.

With the coating material under pressure it is possible to change the spray instantly from one material to another or to blend them as desired without having to cease operations and change containers and nozzles.

Having now described the invention and the preferred form of embodiment thereof it is to be noted that the said invention is to be limited not to the specific details herein set forth but only by the scope of the claims which follow.

I claim:—

1. Means for coating comprising a spray nozzle, means for supplying air under pressure to said nozzle, means for supplying a plurality of coating materials to said nozzle under pressure and a control for each coating material supply, each of said controls also controlling the air supply.

2. In a spray device a nozzle, an air conduit leading to said nozzle, a plurality of conduits for liquid coating material also leading to said nozzle, valves in each of said conduits, and control levers, each connected in operating relation to the valve in the air conduit and to one of the other valves.

3. In a spray device a nozzle, an air conduit leading to said nozzle, a plurality of conduits for liquid coating material also leading to said nozzle, valves in each of said conduits, and control levers, each connected in operating relation to the valve in the air conduits and to one of the other valves, together with means for supplying compressed air to said air conduits and means for supplying a separate coating material under pressure to each of the other conduits.

RALPH E. BATEMAN.
